METHOD AND APPARATUS FOR POLISHING
TRAVELING FLAT GLASSJames Harris Griffin, St. Helens, England, assign-
or to Pilkington Brothers Limited, Liverpool,
England, a limited companyApplication February 3, 1937, Serial No. 123,816
In Great Britain February 5, 1936

12 Claims. (Cl. 51—112)

This invention relates to polishing method and apparatus operating to polish both surfaces of traveling flat glass and has for its object a form of polishing apparatus of reduced cost.

5 In polishing apparatus operating to polish simultaneously both surfaces of a traveling strip of flat glass, the tools operate in pairs, one of each pair on one surface and one opposite to it on the other surface, so that each serves to support the strip against the pressure exerted by the other. In the case of tools having an iron operating surface employing an abrasive such as sand with a considerable amount of water, hereinafter termed grinding tools, the strip is 10 cooled by the water and by conduction through the iron operative surface, but in the case of tools employing a polishing medium such as rouge with a felt or other non-metallic operative surface (hereinafter termed polishing tools) 15 with which only little water can be used, the glass becomes heated to such a degree that it is liable to crack. Undue heating can be avoided by reducing the energy supplied to the polishing tools, but this means that the number of tools 20 has to be increased, with consequent increase in the cost of the apparatus.

According to the invention, the polishing tools are in two pluralities, one plurality operating on one side of the strip and the other on the other side of another portion of the strip, and means are provided opposite each plurality for supporting the strip against the pressure exerted by the tools of the plurality. The supporting means may be a roller bed or it may be a series 30 of tables, and the tables may slide on or under guides with means for removing a table from the series at the end of each plurality and adding it to the series at the start of the said plurality.

It is found that the energy supplied to each 40 tool can be considerably greater when work is being done on only one side of the strip than when tools operate on both sides opposite to each other. Thereby the number of tools required is considerably less and the cost of the apparatus, after allowing for the cost of the supporting means, is less.

In the accompanying drawing—

Figure 1 is a side elevation of a portion of a 50 grinding and polishing machine, shown diagrammatically in that the supporting framework and driving gear are omitted;

Figures 2 and 2a are similar views of an alternative constructional form of the invention, 55 Figure 2a being a continuation of Figure 2;

Figure 3 is an end view of Figure 2 from the left, parts being omitted; and

Figure 4 is a section taken on the line 4—4 of Fig. 2.

Referring to Figure 1, the continuous strip of glass 1 passes through a plurality of pairs of grinding tools, the two tools of each pair operating on the upper and under sides of the strip respectively, so that each serves to support the strip against the pressure exercised by the other; the last pair of grinding tools of the machine is shown at 2. The strip is driven through the machine by pairs of driving rollers 3. The direction of travel of the strip is from left to right. To the right of the last pair of grinding tools 2, where the strip is shown broken away, a suitable length is left free for washing the strip free of sand. The strip 1 then passes under a roller bed 4, which serves as support against the pressure of the polishing tools 5 operating 20 on the underside of the strip. The strip then passes over a roller bed 6, which forms a support against the pressure of the polishing tools 7 operating on the upper side of the strip. Three polishing tools 5 and three polishing tools 7 are 25 shown in the drawing, but in practice from twelve to fifteen tools are required to operate on each side of the strip. The whole number of tools required to operate on one side of the strip may be in one group, followed by a group of those 30 required to operate on the other side, or the two kinds of tools may be in smaller groups, alternating one with the other. The rollers 4 and 6 may be idle rollers or they may be driven at the speed of travel of the strip. Alternatively, 35 a driven belt may be employed as direct support for the strip, the belt passing between the strip and the roller beds 4 and 6. The pairs of driving rollers 3 are then not employed in the polishing section of the machine.

Referring to Figures 2, 2a and 3, the last pair of grinding tools is not shown, but is to the left of Figure 2. In this form of construction, a series of tables 8 is employed to support the strip 1 against the pressure of the polishing 45 tools 5 and 7. The tables 8 slide on upper guides 9 in Figure 2 and on lower guides 10 in Figure 2a. The end view of a table 8 is seen in Figure 3 in a position above the machine, while being transported. The guides 9 engage the table at 50 the surfaces 11. Each table is provided with a rack 12, which is engaged by a pinion 13, shown in dotted lines in Figures 2 and 2a. By means of the pinion 13, the series of tables is driven along the guides 9. Each table 8, after it has 55

passed over the last polishing tool 5, continues to travel with the strip (being pushed by the tables behind it) and rests on it, the strip being then supported by the roller bed 14. A similar 5 roller bed 14 supports the strip to the left of the first polishing tool 5. The table 8, when above this roller bed, comes into an elevator 15, by which it is raised to the level of a runway 16, and is thereby transported to a position be- 10 hind the first polishing runner, where it enters a second elevator 17. A table 8 is shown in position in the elevator 17 at the left hand of Figure 2, and the end view thereof is shown in Figure 3. As seen in this figure, the elevators 15 and 17 support the table by rollers 18 engag- 15 ing it at its edges, the rollers 18 being far enough apart to pass over the strip and its supporting rollers 14.

When a table 8 under the guides 9, has reached 20 the position shown at the left of Figure 2, the elevator 17 is operated to lower another table 8 on to the strip. The table then resting on the strip is pushed into contact with the preceding table under the guides by a pusher 19 operated by a 25 pneumatic cylinder or the like 20, and pressure is exerted by the pusher 19 until the rack 12 of the table comes into engagement with the pinion 13. When the table has passed completely under the guides 9, the elevator 17 is raised to the position shown, where it is ready to receive another 30 table from the runway 16.

In Figure 2a, showing the arrangement where the polishing tools 7 operate on the upper side of the strip, the table transporting devices are 35 similar, though the elevators are of slightly different construction. The elevator 21 receives a table when it is clear of the last polishing tool and delivers it to the runway 22, which transports it to the elevator 23, by which it is raised 40 to the level of the strip. The pusher 19 then brings it into contact with the preceding table on the guides 10.

Alternatively, the tables may be linked together to form an endless chain, the tables being sup- 45 ported by guides or rollers when supporting the strip against the pressure of the tools.

Having described my invention, I declare that what I claim and desire to secure by Letters Patent is:

50 1. Apparatus for polishing a continuous strip of glass on both sides simultaneously comprising a plurality of pairs of rollers adapted to drive the strip through the apparatus without reversing the strip face for face, a plurality of pairs 55 of tools operating with sand and water, the two tools of each pair operating on the two sides of the strip one opposite to the other, two groups of tools operating with rouge and water, arranged respectively on opposite sides of the traveling 60 strip and operating simultaneously thereon, one group facing in one direction to operate on the obverse side of the strip and the other group facing in the opposite direction to operate on the reverse side of said strip, the tools of one group being offset with reference to the tools of the other 65 group so as thereby to operate on the traveling strip at different portions of its length, and non-polishing means arranged directly opposite each group and adapted to support the strip against the pressure exerted by the tools of the group.

70 2. Apparatus for polishing a continuous strip of glass on both sides simultaneously comprising a plurality of pairs of rollers adapted to drive the strip through the apparatus without revers-

ing the strip face for face, a plurality of pairs of tools operating with sand and water, the two tools of each pair operating on the two sides of the strip one opposite to the other, two groups of tools operating with rouge and water, arranged respectively on opposite sides of the traveling strip and operating simultaneously thereon, one group facing in one direction to operate on the obverse side of the strip and the other group facing in the opposite direction to operate on the reverse side of said strip, the tools of one group being offset with reference to the tools of the other group so as thereby to operate on the traveling strip at different portions of its length, and a series of tables arranged directly opposite each group and adapted to support the strip against the pressure exerted by the tools of the group. 15

3. Apparatus as in claim 2 comprising guides adapted to support the tables and means for removing a table from the series of tables at the 20 end of each group of tables and adding it to the series at the start of the said group.

4. Apparatus for polishing a continuous strip of glass on both sides simultaneously comprising a plurality of pairs of rollers adapted to drive 25 the strip through the apparatus without reversing the strip face for face, a plurality of pairs of tools operating with sand and water, the two tools of each pair operating on the two sides of the strip one opposite to the other, two groups of tools operating with rouge and water, arranged respectively on opposite sides of the traveling strip and operating simultaneously thereon, one group facing in one direction to operate on the obverse side of the strip and the other group facing in the opposite direction to operate on the reverse side of said strip, the tools of one group being offset with reference to the tools of the other group so as thereby to operate on the traveling strip at different portions of its length, and a 40 plurality of moving supports arranged directly opposite each group of tools and adapted to support the strip against the pressure exerted by the tools of the group. 35

5. Apparatus for polishing a continuous strip 45 of glass on both sides simultaneously comprising a plurality of pairs of rollers adapted to drive the strip through the apparatus without reversing the strip face for face, a plurality of pairs of tools operating with sand and water, the two tools 50 of each pair operating on the two sides of the strip one opposite to the other, two groups of tools operating with rouge and water, arranged respectively on opposite sides of the traveling strip and operating simultaneously thereon, one group 55 facing in one direction to operate on the obverse side of the strip and the other group facing in the opposite direction to operate on the reverse side of said strip, the tools of one group being offset with reference to the tools of the other group so as thereby to operate on the traveling strip at different portions of its length, and a bed arranged directly opposite each group and adapted to support the strip against the pressure 60 exerted by the tools of the group, the portions of the bed contacting with the strip moving with the strip. 65

6. Apparatus for polishing a continuous strip of glass on both sides simultaneously comprising means adapted to drive the strip through the apparatus without reversing the strip face for face, a plurality of pairs of disc tools made of cast iron operating with their flat surfaces in contact with the glass with sand and water, the two tools of each pair operating on the two sides of the 70

- strip one opposite to the other, two groups of disc tools covered with a non-metallic material operating with their flat surfaces in contact with the glass with rouge and water, arranged respectively on opposite sides of the traveling strip and operating simultaneously thereon, one group facing in one direction to operate on the obverse side of the strip and the other group facing in the opposite direction to operate on the reverse side of said strip, the tools of one group being offset with reference to the tools of the other group so as thereby to operate on the traveling strip at different portions of its length, and a plurality of moving supports arranged directly opposite each group of tools and adapted to support the strip against the pressure exerted by the tools of the group.
7. Apparatus for polishing a continuous strip of glass on both sides simultaneously comprising a plurality of pairs of rollers adapted to drive the strip through the apparatus without reversing the strip face for face, a plurality of pairs of tools operating with sand and water, the two tools of each pair operating on the two sides of the strip one opposite to the other and being adapted to conduct away from the glass heat generated during the grinding operation, two groups of tools operating with rouge and water, arranged respectively on opposite sides of the traveling strip and operating simultaneously thereon, one group facing in one direction to operate on the obverse side of the strip and the other group facing in the opposite direction to operate on the reverse side of said strip, the tools of one group being offset with reference to the tools of the other group so as thereby to operate on the traveling strip at different portions of its length, and non-polishing means arranged directly opposite each group and adapted to support the strip against the pressure exerted by the tools of the group.
- 40 8. Apparatus for polishing a continuous strip of glass on both sides simultaneously comprising a plurality of pairs of rollers adapted to drive the strip through the apparatus without reversing the strip face for face, a plurality of pairs of tools operating with sand and water, the two tools of each pair operating on the two sides of the strip one opposite to the other, two groups of tools operating with rouge and water, arranged respectively on opposite sides of the traveling strip and operating simultaneously thereon, one group facing in one direction to operate on the obverse side of the strip and the other group facing in the opposite direction to operate on the reverse side of said strip, the tools of one group

being offset with reference to the tools of the other group so as thereby to operate on the traveling strip at different portions of its length, and a roller bed arranged directly opposite each group and adapted to support the strip against the pressure exerted by the tools of the group.

9. A method of polishing a continuous strip of glass on both sides simultaneously while the strip is in motion, characterized in that the simultaneous polishing operations are effected in offset regions on opposite sides of the strip without reversing the strip face for face.

10. A method of polishing a continuous strip of glass on both sides simultaneously while the strip is in motion, characterized in that the simultaneous polishing operations are effected in offset regions on opposite sides of the strip without reversing the strip face for face, and in that each of said different portions of the strip is supported on the side opposite directly against the pressure exerted during the polishing operation.

11. Apparatus for polishing a continuous strip of glass on both sides simultaneously, comprising a plurality of pairs of rollers adapted to drive the strip through the apparatus in a horizontal plane, a plurality of pairs of tools operating with sand and water, the two tools of each pair operating on the two sides of the strip one opposite to the other, a group of tools operating with rouge and water on the upper surface of the strip and non-polishing means engaging the lower surface below the said group of tools and adapted to support the strip against the pressure exerted by them, and a second group of tools simultaneously operating with rouge and water on the lower surface of the strip and non-polishing means engaging the upper surface above the said second group of tools and adapted to support the strip against the pressure exerted by them.

12. Apparatus for polishing a continuous strip of glass on both sides simultaneously comprising means for driving the strip through the apparatus in a horizontal plane, a group of tools operating with rouge and water on the upper surface of the strip and non-polishing means engaging the lower surface of the strip below said group of tools to support the strip against the pressure exerted by said tools, and a second group of tools simultaneously operating with rouge and water on the lower surface of the strip and non-polishing means engaging the upper surface of the strip above said second group of tools to support the strip against the pressure exerted by said tools.

JAMES HARRIS GRIFFIN.
